UNITED STATES PATENT OFFICE

WILLIAM A. GERSTMYER AND WEAVER R. CLAYTON, OF BALTIMORE, MARYLAND, AS
SIGNORS TO COLUMBIA ENGINEERING AND MANAGEMENT CORPORATION, OF NEW
YORK, N. Y., A CORPORATION OF OHIO

PRODUCTION OF PROPYLENE

No Drawing.

Application filed December 14, 1929. Serial No. 414,218.

This invention relates to decomposition of hydrocarbons and the production of other hydrocarbon compounds, and more particularly to thermal decomposition of hydrocarbons boiling between -90° and 36° C., especially butane, to produce propylene.

Commercial butane consists of a mixture of butane, iso-butane and a small amount of propane, present as an impurity. The proportions of these three constituents vary considerably, depending upon the source of the natural gases from which the commercial butane is condensed. Typical analyses of commercial butanes include 1 to 5% of propane, 5 to 10% of iso-butane and 87 to 94% of butane. Such materials may be treated in accordance with the invention to produce propylene and other hydrocarbon compounds or mixtures thereof including pentane, butane, propane and ethane may be utilized likewise for the purpose of the invention.

It is known that hydrocarbons such as butane undergo decomposition or cracking when heated to relatively high temperatures. The usual reactions may be indicated:

According to reaction 1, propylene and methane are the products; ethylene and ethane are the products of the second reaction and butylene and hydrogen are produced by the third.

We have discovered that the cracking of hydrocarbons such as butane at high temperatures can be directed to produce larger proportions of propylene when the operation is conducted in the presence of copper. Thus if a hydrocarbon, such as butane, is heated in a copper tube or in a tube lined with copper to an appropriate temperature, e. g., 700° C., the ratio of propylene to ethylene by volume in the product is 7.8:1, whereas if a chrome steel tube is used the ratio of propylene to ethylene is only 2.3:1.

It is not essential that the copper be pure, as brass tubes produce a similar effect, that is, the product will contain a ratio of propylene to ethylene of 6:1. Copper in any form

may be used to direct the reaction, for example, copper filings or turnings, or filings or turnings of brass or other copper alloys can be employed in a tube of any material which does not affect the reaction adversely. The essential factor is the presence of copper in such form as to permit effective control of the vapors therewith at the cracking temperature.

In the preferred form of the invention, the vapors of butane or mixtures of butane with other hydrocarbons are conducted through a reaction tube or chamber a portion of which is heated to an appropriate temperature. Copper is present in the chamber so that the vapors contact therewith. A temperature of 700° C. is satisfactory, but the temperature is not critical and may vary widely with reference particularly to the rate of flow. The temperature and rate of flow can be increased or decreased simultaneously to afford the best cracking conditions which have been found by experiment to be such that for every volume of butane passed the volume of cracked gases is increased 0.29. This is expressed by the ratio of the volume of butane to the volume of the product which should be about 1:1.29. Under such conditions a yield of about 18% by volume of propylene should be obtained, based on the volume of the gaseous mixture entering the chamber.

As an example of the invention, commercial butane is passed through a reaction tube of copper or steel lined with copper about three feet long and one inch internal diameter. About one third of the tube is heated to about 700° C. The rate of flow is such that the vapor remains in the cracking zone for about 1.7 seconds. The product will contain about 7.8 parts by volume of propylene to each part by volume of ethylene.

No satisfactory explanation of the mechanism of the reaction or the exact effect of copper thereon is available. Presumably copper acts as a catalyst of the propylene forming reaction and thus directs it so that higher ratios of propylene are produced in the presence of copper than are obtainable otherwise.

Various changes may be made in the details

of operation or procedure and particularly in the apparatus employed, without departing from the invention or sacrificing the advantages thereof.

5 We claim:

1. The method of producing propylene which comprises thermally decomposing a mixture of aliphatic hydrocarbons consisting essentially of butane and iso-butane by passing the material through a heated chamber in the presence of copper at a rate such that the ratio of the initial volume to the volume of the gaseous product is about 1:1.29.

10 2. The method of producing propylene which comprises thermally decomposing a mixture of aliphatic hydrocarbons consisting essentially of butane and iso-butane by passing the material through a heated chamber of about one inch internal diameter in the presence of copper for a period of about 1.7 seconds.

15 3. The method of producing propylene in a gaseous mixture containing 18% or over of propylene and from two to three percent of ethylene which comprises thermally decomposing a mixture of aliphatic hydrocarbons consisting essentially of butane and iso-butane by passing the material through a heated chamber in the presence of copper at a temperature of about 700° C. and for a period of about 1.7 seconds so that the ratio of the initial volume to the volume of the gaseous product is about 1:1.29.

20 4. The method of producing propylene which comprises thermally decomposing a mixture of aliphatic hydrocarbons consisting essentially of butane and iso-butane by passing the material through a heated chamber in the presence of copper at a temperature of about 700° C. so that the ratio of the initial volume to the volume of the gaseous product is about 1:1.29.

In testimony whereof we affix our signatures.
